UNITED STATES PATENT OFFICE.

ERNST PAUL LEHMANN, OF BRANDENBURG-ON-THE-HAVEL, GERMANY.

TOY WHEEL.

1,018,573.

Specification of Letters Patent. Patented Feb. 27, 1912.

Application filed August 16, 1910. Serial No. 577,518.

To all whom it may concern:

Be it known that I, ERNST PAUL LEHMANN, a subject of the King of Prussia, and resident of No. 6 Plauerstrasse, Brandenburg-on-the-Havel, in the Kingdom of Prussia, German Empire, have invented certain new and useful Improvements in Toy Wheels, of which the following is a specification.

10 My invention relates to an improved wheel for toys of that class, in which the wheel is composed of two halves, preferably made of sheet-metal or any other suitable material, the said two half-wheels having 15 flanges turned up at right angles from the plane and the edges of said flanges of the two halves being jointed to each other to form a hollow circular box or casing which serves as a wheel for toys or as a sheave or 20 drum or roller to be employed in the construction of toys, particularly of mechanical toys.

The purpose of this invention is to provide a wheel or the like of this kind, the two 25 halves of which have a firm hold upon each other and are not liable to be deformed or destroyed in use, as other toy-wheels very frequently used to be. The periphery of the wheel, or drum or roller, according to this 30 invention, has no projecting portions but presents an even rolling surface enabling the toy to run smoothly and without objectionable friction upon the floor, or table or any surface upon which the toy is being 35 placed.

The manufacture of toy-wheels according to this invention is very cheap and requires no soldering, riveting or welding, the joint between the two halves of the wheel being 40 obtained by tongues or lugs projecting from the edge of one half and engaging slits or recesses in the other half, which tongues or lugs, when engaged in the slits or recesses of the opposite half, are bent to firmly hold 45 one half of the wheel against the opposite half.

In the accompanying drawings, Figure 1 is a central vertical section through a toy wheel constructed according to this invention, the section line being taken on line 50 A—A of Fig. 2. Fig. 2 is a side elevation of the toy-wheel, seen from the left toward the right of Fig. 1. Fig. 2^a is a section through the wheel taken on line B—B of Fig. 2. Fig. 3 is a vertical section through the two halves of the wheel before they are

jointed to each other. Fig. 4 is a side-view of one of the halves of the wheel. Figs. 5, 6, 7 and 8 serve to illustrate a modification of this invention, Fig. 5 being a central vertical section through the wheel on line D—D of Fig. 6; Fig. 8 being a section on line E—E of Fig. 6. Fig. 7, is a similar section on line D—D of Fig. 6 and showing a modification of the same.

Referring to Figs. 1, 2, and 2^a, *a*, and *b*, are the two halves of the wheel, stamped from sheet-metal or other ductile material; a central hole *c*, may be punched into said halves to receive the wheel-axle, and an annular recess *d*, may also be pressed into the metal of the said halves, but neither the central hole, nor the recess *d*, is essential nor forms part of this invention. Both of the half-wheels *a*, *b*, have flanges *e*, *f*, turned up at right angles to the plane of the wheel, and the said flanges, when laid against each other, as fully shown in Figs. 2, and 2^a, are flush with each other and form a plane and even periphery of the wheel. To join the two halves *a*, and *b*, to each other, one of said halves, say *b*, has tongues or lugs *g*, projecting from the edge of its flange *f*, and in the other half, *a*, corresponding slits *h*, are provided, through which the said tongues or lugs *g* are made to pass and project. The projecting ends of said tongues or lugs, then, being bent down to the surface of the wheel, the two halves are firmly engaged to each other, without soldering or riveting or other means. The tongues or lugs *g* are not projecting in the plane of the flange *f*, but are set off to form a shoulder *i*, as shown in Fig. 1, against which the edge of the flange *e* of the other half *a* will rest; the said tongues or lugs *g*, therefore, provide an additional strength to the circumference of the wheel.

While, according to Figs. 1, 2, and 2^a, the two halves *a*, and *b*, of the wheel are not equal to each other, one carrying the lugs or tongues *g*, and the other being provided with an equal number of slits *h*, the said halves, according to Figs. 3 and 4, are slightly modified in that each of the two half-wheels *a*, and *b*, have projecting tongues or lugs *g*, and each of them is provided with corresponding slits, *h*, whereby the two halves are mutually engaging each other and the bent ends of the said tongues or lugs project from either side of the wheel.

The modification illustrated by Figs. 5, 6, and 8, differs from the construction before described in that the lugs or tongues *g* are not made to pass through slits below the periphery of the wheel, but overlap said periphery and fit or are sunk into recesses *j* on said periphery, as clearly shown in Fig. 6, the uppermost of the tongues in said figure being shown in section to clearly show the recess *j* in the periphery. The said recesses *j*, are just filled by the tongues or lugs engaging therewith, thus providing a flush or even surface of the periphery of the wheel.

According to Figs. 5, and 8, only one of the two halves *a*, and *b*, has tongues or lugs *g*, formed to the edge of its flange, and the said tongues or lugs overlap the outside periphery of the counter-half wheel.

Fig. 7 illustrates another modification, according to which both half-wheels *a*, and *b*, have tongues *g* formed on the edge of their flange. In this case, the said tongues projecting from the edge of the half-wheel *b* are adapted to overlap the periphery of the half-wheel *a* and to engage its recesses *j*, while the tongues or lugs *g* of the other half-wheel *a* extend in a straight line to or nearly to the bottom of the counter-half wheel *b*. The inside-tongues of the half-wheel *a*, in this case, serve as a counter-support of the other half-wheel *b*, adapted to strengthen the whole structure, even if the recesses *d*, in the sides of the wheel are not provided for.

Should the two halves *a*, and *b*, of the wheel become forcibly pushed or pressed against each other, the extension of the tongues *g* of the half *a*, up to the inside surface of the wheel-half *b*, will prevent the flanges of the two halves from overlapping each other or slipping one over the other or breaking their vertical joint.

It will be noted that in all of the forms shown and described the tongues extending from the lateral flange of one of the half-wheels engage receiving seats on the opposite half-wheel, which receiving seats do not extend beyond the periphery of the half-wheel. Thereby, when the parts are assembled and fastened the tongues will in no case form a projection extending beyond the periphery of the half-wheel, so that a smooth wheel periphery is formed, whether the receiving seats be in the form of slits *h* as in Figs. 1 to 4 or in the form of peripheral recesses as in the remaining figures.

I claim as my invention:

1. In a wheel, a half-wheel comprising a

disk-portion provided with an annular flange extending laterally from the disk, 60 said flange being provided with tongues extending beyond the same, in combination with a second half-wheel also comprising a disk-portion and a lateral annular flange and provided with receiving seats extending 65 entirely within the periphery of the said second half-wheel, the tongues on the first half-wheel engaging said seats on the second half-wheel.

2. In a wheel, a half-wheel comprising a 70 disk portion and an upturned annular flange formed on the same, said flange being provided with tongues extending beyond the same, in combination with a second opposite half-wheel also comprising a disk-portion and an upturned annular flange and provided with peripheral recesses in the flange, the tongues on the first half-wheel 75 engaging the recesses on the second half-wheel.

3. A toy-wheel comprising two half-wheels of equal diameter, each half-wheel having a circular upturned flange co-acting with the flange of the opposite half-wheel to form the periphery of the wheel, tongues 85 formed on the edge of the flange of at least one of the two half-wheels, recesses formed in at least one of the two half-wheels, said recesses being adapted to be engaged by the said tongues of the opposite half-wheel, and 90 a bent end formed to the end of said engaging tongues, to hold the two half-wheels against each other, substantially as and for the purpose set forth.

4. A toy-wheel comprising two half-wheels of equal diameter, each half-wheel having an upturned flange co-acting with the flange of the other half-wheel to constitute the periphery of the wheel, recesses formed across the flange of at least one of 100 the two half-wheels, tongues projecting from the flange of at least one of the two half-wheels, said tongues being adapted to engage and fill the said recesses in the flange of the opposite half-wheel, and a bent portion formed on the end of said tongues, to 105 hold the two half-wheels against each other, substantially as and for the purpose set forth.

In witness whereof I have hereunto set 110 my hand in presence of two witnesses.

ERNST PAUL LEHMANN.
